UNITED STATES PATENT OFFICE

THEODORE H. WITTLIFF, OF CLEVELAND, OHIO

FURNITURE BRACE AND CONTROLLING DEVICE

Application filed June 18, 1925. Serial No. 37,946.

This invention, as indicated, relates to a furniture brace and controlling device. More particularly it comprises a brace particularly adapted for use on beds wherein a box spring is employed. However, the construction may be applied to articles other than those illustrated, as will be obvious.

It has heretofore been proposed to provide a tensioning device for beds and the like, which would draw the corner posts against the side and end wall members. In most instances such tension is applied in the plane of the side frame members. However, where upholstering, drawers, or box springs would prevent the positioning of such tension device in the plane of the side members, it is necessary that the tension be applied in a lower plane, using equalizing devices to transfer the pressure to the plane of the side frame members, as is shown in a co-pending application filed by me.

Such means to transfer the tension to the plane of the side frame members, while entirely satisfactory from an operative standpoint, may in some instances be open to the objection that the tensioning device is displayed conspicuously beneath the box-spring, and detracts from the artistic general appearance of the bedstead, or other article of furniture.

The present invention has for its principal object the provision of a furniture brace which will draw the end and side frame members firmly against the corner posts, and which will at the same time be concealed within the space adjacent the side and end frame members.

A further object of the invention is to provide a tensioning device of the character mentioned, which will permit a box spring to be used upon a bedstead with as much freedom as though a bed brace were not applied thereto.

Another object of the invention is to provide means operating upon the same principle as that above described, which is particularly adapted for use with metal beds, and includes a bowed corner fixture which co-operates with a single flexible tensioning element lying parallel to and closely adjacent the

side and end members of a bed frame, and permitting the use of a box spring or similar construction, without interference with the application of suitable tension to the bed frame in the plane of the side members.

Another object of the invention is to provide a tensioning means for applying tension to the corner posts as well as to the side and end frame members.

A further object of the invention is to provide convertible clips which admit of the use of the ordinary spring or a box spring within the same bed frame, and also facilitating shipment of the side frame members, when the bed is to be transported in knock-down form.

A still further object of the invention is to provide a double wire tensioning means cooperating with a turn buckle at one side or end of the bed and with an equalizing device upon the opposite side or end of the bed, whereby an extremely high degree of tension may be applied to said bedstead, and equal draft upon all portions of the tensioning device be provided for.

Other and further objects of the invention will appear in the course of the following description. To the accomplishment of the foregoing and related ends, said invention then consists of the means hereinafter fully described and particularly pointed out in the claims, the annexed drawings and the following description setting forth in detail certain mechanism embodying the invention, such disclosed means constituting, however, but several of various mechanical forms in which the principle of the invention may be used.

In said annexed drawings:

Fig. 1 is a perspective view partially in section, showing the application of one form of my invention to the frame of an article of furniture; Fig. 2 is a fragmentary perspective view showing the flexible elements in their relation to the corner construction of an article of furniture; Figs. 3 and 4 are perspective views, respectively, of the cable engaging plate and bracket attachment therefor, which are applied to the side and end members of a bedstead; Figs. 5 and 6 are

views similar to Figs. 3 and 4, showing a modified form of construction; Fig. 7 is a side view of the type of plate disclosed in Fig. 5 when applied to a metal bed equipped with a box spring; Fig. 8 is a view similar to Fig. 7 showing the bracket attached to the plate shown in Fig. 5 in position to support a standard bed spring and mattress; Fig. 9 is a view similar to Fig. 7, showing the device applied to a wooden bed; Fig. 10 is a view similar to Fig. 8 showing the device applied to a wooden bed; Fig. 11 is an enlarged detail view showing a modified form of turn buckle, somewhat similar to that disclosed in Fig. 1; Fig. 12 is a perspective view of a looped form of cable construction, with a modified form of turn buckle and equalizing device; Fig. 13 is an enlarged view of a modified form of equalizing device; Fig. 14 is a modified form of tensioning device somewhat similar to that disclosed in Fig. 12; Fig. 15 is a side elevation of a modified form of tensioning device in assembled relation; Fig. 16 discloses one member of said tensioning device and Fig. 17 discloses the other member of said tensioning device shown in Fig. 15; Fig. 18 is a fragmentary perspective view partly in section of a modified form of tensioning device applied to a metal bed frame; Fig. 19 is a fragmentary plan view showing a device of the character shown in Fig. 18; Fig. 20 is a fragmentary perspective view of a still further modification of the tensioning apparatus; and Fig. 21 is a top plan view of a construction of the character shown in Fig. 20.

In Fig. 1, a construction, particularly suitable for application to a wooden bed, is disclosed. In said figure a bed frame comprising corner posts 1, side members 2, 3 and end members 4, 5, is shown. At the ends of each of the end and side frame members, clips 6 are attached, preferably by means of screws 7, or similar fastening elements as is more particularly shown in Fig. 2. Each clip preferably comprises a sheet metal plate having a projecting tongue 8 at its upper edge, bent so as to receive a cable or tensioning wire, and having a pair of similar tongues, 9, 10 formed from a struck up portion of the metal adjacent its lower central portion. A plurality of screw holes 11, are formed through the plate to receive the screws 7, or similar fastening elements.

The details of the clip or plate construction are shown in Fig. 3 of the drawing, and in Fig. 4 thereof a bracket member 12 adapted to co-operate therewith is illustrated. Said bracket member is preferably formed from a sheet metal blank so folded as to provide a top horizontal supporting plate 13, having a downwardly extending tongue 14 at its rearward edge, and having a pair of tapered side wings 15, with angularly disposed end extensions 16, which serve as braces for supporting said top plate. The downwardly extending tongue 14 at the rearward edge of the top plate is adapted to be engaged behind the struck up member 9 of the plate 6 so as to support the bracket member 12 in a position to project inwardly from the side and end members of the bed frame, as is clearly shown in Fig. 1.

A modified form of plate and supporting bracket is disclosed in Figs. 5 to 10 inclusive. In said construction, the plate 21 is provided with a pair of lateral ears 22, which project forwardly above the face of the plate, and are apertured adjacent their ends to receive a securing pin 23. At the upper edge of the plate, a projecting tongue 24 is provided, and adjacent the lower portion of said plate, a similar tongue 25 is struck up from the body of the plate, said respective tongues being adapted to receive the upper and lower tensioning cables or wires, as will be presently described.

The plate 21 is provided with screw holes 26 to receive the screws or fastening elements in the same manner as the plate 6 above described. A removable bracket member 27, comprising a top plate 28 and downwardly turned rearward extension thereof 29, and a pair of side wings 30, is provided, said side wings having aligned apertures 31 formed upon opposite sides through which the supporting pin 29 is adapted to be inserted. The supporting bracket may thus be securely fastened to the plate 21, or readily removed therefrom, as may be required.

The purpose of the plate and bracket arrangements, above described, is clearly shown in Figs. 7 to 10 inclusive. Thus, in Fig. 7, wherein a bracket 21 is shown as secured to a side rail 33 of a metal bed, the bracket 27 is omitted in order to permit the use of a box spring 34, the lower portion of which projects past the position of the supporting bracket, and the projecting upper edge of which rests upon the top flange of the side rail in the usual manner. When the same bed is to be used to support a spring in the usual manner, as distinct from a box spring, the bracket 27 is attached to a plate 21 by means of the pin 23, as is shown in Fig. 8. The spring frame 35 will then rest upon the top plate of the bracket, and the spring 36 will support a mattress 37 of the usual type. In Fig. 9, the construction illustrated in Fig. 7 is shown applied to the side rail 41 of a wooden bed, the other parts being substantially the same as those illustrated in Fig. 7. In Fig. 10 the construction shown in Fig. 9 is illustrated with the supporting bracket 27 in place and supporting a standard spring frame 35, spring 36 and mattress 37 in the manner illustrated in Fig. 8.

As will be noted, in Figs. 1, 2, and 7 to 10, inclusive, the cable engaging tongues are

adapted to engage an upper and lower cable length and hold the same against the side or end members at such points in close proximity to the inner faces of the side and end members of the bed frame.

In the form of construction shown in Fig. 1, the tensioning device comprises a pair of flexible elements shown in the form of wires, 42, 43, which are looped over the ends of an equalizing plate 44, at one end of the bed, positioned adjacent the central part and inner side of the end member 5, and provided at their free ends with a series of links 45, 46, which are adapted to be engaged respectively over the ends of T-shaped terminal elements 47, 48 forming part of a turn buckle, having an internally screw threaded barrel 49, engaged over the oppositely threaded shanks 51, 52 of said T-shaped terminals. The barrel 49 is provided with a transverse aperture through which an operating bar 53 is engaged. Said operating bar is provided at either end with an enlargement 54, which prevents disengagement from said barrel shaped member, and which permits the ready sliding of said bar through said barrel during the successive steps of tightening or loosening the tension upon the cables by means of said turn buckle.

The equalizing device 44 comprises a plate, preferably of stamped sheet metal, having its ends curved so as to provide arcuate cable engaging terminals 55 at either end.

From the construction just described, it will be obvious that when the upper length of wire 42, 43 is engaged with its central portion over the terminals, 55, and with its intermediate portions engaged behind the upper and lower tongues, respectively, of the plates 6, with the chain loops upon the free end of said wires engaged over the opposite ends of the T-heads, thereby turning said turn buckle barrel in a direction to bring said T heads together, that an equal degree of tension will be applied to the wires, and the side and end members of the bed frame will be drawn into contact with their respective corner posts. In this manner, all lost motion which may be developed between the frame members of a bedstead, or similar article of furniture, may be readily removed by placing the necessary degree of tension upon the turn buckle.

In Fig. 11 there is shown a modified form of construction of turn buckle, the T heads thereof comprising bars 61, provided with a series of notches 62. The outer sides of said bars are provided with a central depression 63 adapted to be engaged by an enlargement 64 formed on the inner side of a strap-like body portion 65, having the head of a screw threaded member 66, the shank of which is engaged within the barrel 67 of the turn buckle. Upon the outer side of said strap like head, a hook 66 is provided. The barrel

portion of the turn buckle is provided with a transverse aperture 68, through which the pin or operating bar 69 is slidably engaged. At each end of said bar an enlargement 71 is provided, in order to prevent the disengagement of said bar from said barrel, as the same is shifted from end to end in the course of tensioning said turn buckle.

In Fig. 12 of the drawing, there is illustrated a device somewhat similar to that shown in Fig. 1, but a construction wherein the flexible members comprise respectively the wire loops, 72, 73, which are engaged at their respective ends over an equalizing plate 74, and over the Y-shaped terminal 75 of the turn buckle 76. Plates 77 of the type shown in Fig. 3 are attached to the respective side and end frame members adjacent the corner posts and the upper and lower stretches of said loops are engaged respectively with the respective tongues on said plates. The equalizing device as is more particularly shown in Fig. 13 comprises a plate 74 having a flat body portion through which a pair of screw holes are provided to receive fastening screws 78, and is shaped at its respective ends to provide arcuate slots 79, within which the wire loops 72, 73 are respectively engaged.

The turn buckles illustrated in Figs. 12 and 14, each provide Y-shaped cable engaging terminals 75, which lie substantially in the plane of the axial line of said turn buckle. In the form of turn buckle shown in Fig. 14, single wire hooks 81 are provided inside the Y portions thereof, said hooks being intended to permit said turn buckles to be used upon beds of different construction, being adapted either for wooden or metal beds and double or single wire tensioning elements.

In the construction shown in Figs. 15, 16 and 17, a form of tensioning device is disclosed, which permits the tensioning operation to be carried on, irrespective of whether the box spring or standard spring of a bedstead is in position between the frame members. In said construction, two loop engaging members 82, 83, respectively, are provided, the member 82 having a shank 84 adapted to be telescopically engaged within a slide-way 85, provided upon the member 83. The member 82 is provided with a series of teeth 86 upon one side adjacent the end of the shank portion, and at its opposite end carries a Y-shaped cable engaging yoke 87. A hook 88 may be formed centrally of said Y-shaped portion in a manner similar to the hook 81 shown in Fig. 14. The member 83 is provided with a Y-shaped portion 91 similar to the Y-shaped head on the shank 84, and likewise has a central hook 92. The body portion of the member 83 is formed by folding the edges about an extension 93 upon said head and pinning the same thereto. The upper edge of the member 83 is provided with

a cut-away portion 94 adjacent its free end and a pair of up-standing ears 95 are positioned at an intermediate point adjacent said cut-away portion. A dog 96 is pivoted in said ears and is adapted to engage the rack teeth 86. On the under side of the body portion of the member 83, opposite the yoke 91 thereof, an extension 97 is provided to which is pivoted a lever 98, carrying at its upper end a pivoted pawl 99.

As will be obvious, the shifting of the lever will serve to move the member 82 telescopically within the member 83 and will thus apply tension to the cables engaged over the respective Y heads 87 and 91. The dog 96 will maintain the adjustment thus brought about until released in the usual manner.

In the form of construction illustrated in Fig. 18, an arrangement particularly suited for use on a metal bed is disclosed. In said construction a pair of straps 101, 102 are provided about the corner posts 103 above and below the side and end rails 104, 105, respectively, and the ends of said straps are secured by means of pins or bolts 106, 107 to a bow shaped member 108, provided on its outer side with a hook 109, over which the flexible tensioning member 111 is adapted to be engaged.

In the form of construction illustrated, the flexible member is preferably formed of a flat metal band or steel tape, one end 112 of which is provided with an eye adapted to engage over one of the terminal elements 113 of the turn buckle 114, and the other end of which is adapted to be received within a clamp 115 after the same has been passed about the opposite terminal 116 of said turn buckle. The free end 117 of said steel tape is passed beneath an eccentric cam lever 118 forming part of said clamping device, and is firmly gripped therein in a manner clearly shown in Fig. 19 of the drawing.

In the construction illustrated, tension is applied to the turn buckle in the usual manner by means of the pin or tensioning bar 121.

In the form of construction shown in Figs. 20 and 21 in place of a steel tape a single wire 122 is shown as the flexible tensioning element. The attachment secured to the corner post 103 is identically the same as that disclosed in Fig. 18. Upon each of the side and end members 104, 105, a plate 123 is secured, the single wire being engaged beneath the central tongue 124 thereof. The turn buckle shown in connection with said construction shown in Fig. 20 is of the type illustrated in Fig. 14 and the single flexible tensioning member is engaged upon the hook 81 thereof. In Fig. 21 the course of the single flexible tensioning member is shown diagrammatically, and it will be noted that inward tension is placed upon the post 103,

as well as upon the side and end members 104 and 105 respectively.

Other modes of applying the principle of my invention may be employed instead of those explained, change being made as regards the mechanism herein disclosed, provided the means stated by any of the following claims or the equivalent of such stated means be employed.

I, therefore, particularly point out and distinctly claim as my invention:

1. A tensioning device having in combination a frame having corner posts and horizontal frame members securing members adapted to be attached to said horizontal frame members adjacent the corners of the frame, flexible means forming a closed loop adapted to engage each of said securing members, and to lie substantially parallel to the plane of and spaced from the members of said frame, and unitary means for applying a desired degree of tension to said loop and securing members.

2. A device of the character described, having in combination a plurality of corner posts, side and end frame members disposed between said respective posts, securing members attached to each of said posts, additional securing members attached to the ends of said respective side and end frame members adjacent said corner posts, flexible members forming a closed loop having running engagement with said securing members, and lying adjacent and parallel to the inner faces of said side and end frame members, and means for tensioning said loop and thus applying tension to all the securing members.

3. A device of the character described, having in combination a plurality of corner posts, side and end frame members disposed between said respective posts, double ended clips secured to said end and side frame members adjacent said corner posts, flexible means having running engagement with the upper and lower ends of said clips and means for applying tension to said flexible means.

4. A device of the character described, having in combination a plurality of corner posts, side and end frame members disposed between said respective posts, double ended clips secured to said end and side frame members adjacent said corner posts, flexible means having running engagement with the upper and lower ends of said clips, means for applying tension to said flexible means, and supporting means adapted to be detachably connected with said clips.

5. A device of the character described, having in combination a plurality of corner posts, side and end frame members disposed between said respective posts, double ended clips secured to said end and side frame members adjacent said corner posts, a pair of looped flexible elements engaged over the upper and lower ends of said clips successively about the re-

spective halves of said structure, a tensioning device interposed between the ends of said loops adjacent one side of said frame structure and an equalizing device interposed between said loops adjacent the opposite side of said frame structure.

6. A device of the character described, having in combination a plurality of corner posts, side and end frame members disposed between 10 said respective posts, double ended clips secured to said end and side frame members adjacent said corner posts, a pair of looped flexible elements engaged over the upper and lower ends of said clips successively about a 15 semi-circumference of said structure, a tensioning device interposed between the ends of said loops adjacent one side of said frame structures, a plate slidably positioned adjacent the other side of said frame structure, 20 and a cable engaging means provided at each end of said plate and adapted to be engaged within the loops of said flexible members.

Signed by me this 3rd day of June, 1925.
THEODORE H. WITTLIFF.
